VISUAL CONTROL DEVICE OR THE LIKE

Helmer G. Christenson, South Euclid, Ohio

Application June 9, 1951, Serial No. 230,765

3 Claims. (Cl. 116—135)

1

This invention relates to visual types of control, register, or indicator devices or similar apparatus wherein any desired data can be visually indicated in an easily readable manner.

In large offices, such as insurance offices, where the salesmen are in and out of the office constantly, it is very difficult for the office clerical staffs and management to keep track of the different salesmen and know definitely when they anticipate being in the office again, or whether they are in the office at any given time. Likewise, in other establishments such as auto sales agencies, the salesmen may spend some time in the agency on the floor to greet customers, or they may be in the agency but not on the floor, or else they may be out making calls. Thus the agency would like to know both the present whereabouts and the future planned schedule of its various salesmen.

Furthermore, in many other instances of inventory controls in factories or retail establishments, it is necessary to keep accurate running controls on the inventories of different types of materials or goods in the factory, and such controls or register should be kept currently accurate.

In apparatus of the type referred to, it is necessary that the register or indicator devices be easily adjusted, be accurately maintained, but yet be readily manipulated by persons using the device.

Apparatus similar to that disclosed herein has been proposed heretofore, but such apparatus has not been of sturdy construction, or has not been easily adjusted by the people using the device, or the device may not be accurate in the data recorded. Still other devices of this type may have been cumbersome in size, or have been too fragile for the rough use to which it was subjected, or they may have been objectionable for one or more other reasons.

The general object of the present invention is to avoid and overcome the foregoing and other disadvantages with previous types of register or control devices of the class described, and to provide a device of this class which is characterized by the ready variation of the data recorded thereby and the convenient readability of such data.

Another object of the invention is to provide a control device which is compact and sturdy in construction and which is of attractive appearance.

Still another object of the invention is to provide a control device of the class described where-

2

in movable indicator means can be moved and read from both sides of the control device.

Another object of the invention is to provide a device of the class described wherein a movable marker can readily be replaced when damaged, or wherein markers can easily be added to or removed from the apparatus which is otherwise completely constructed, at any desired time.

The foregoing and other objects and advantages of the invention will be made more apparent as the specification proceeds.

Attention is now directed to the accompanying drawings, wherein:

Fig. 1 is an elevation of a register and control device embodying the principles of the invention;

Fig. 2 is a fragmentary rear elevation of a portion of the device of Fig. 1 when rotated 180° on its vertical axis;

Fig. 3 is a fragmentary horizontal section through a part of the frame taken on line 3—3 of Fig. 1 and showing how the ends of the positioner or carrier bars are secured therein;

Fig. 4 is a fragmentary vertical section through a carrier bar and indicator device taken on line 4—4 of Fig. 1; and

Fig. 5 is a fragmentary elevation of a modification of the invention.

The present invention relates to a control or register device of the class described wherein a frame having an open center portion is provided, a plurality of carrier bars of substantially I-shape in section are in the open center of the frame in parallel relation, means position such carrier bars in spaced relation in the frame, indicator means are slidably engaged with an edge flange of at least one carrier bar, which indicator means project over both face portions of a carrier bar, indicia means are provided on both faces of the carrier bar, and indicia means are positioned on the frame associated with an end portion of each carrier bar.

In order to understand the invention completely, reference should be had to the details of the structure shown in the drawings, and a control or register device of the invention is indicated in general by the numeral 1. This control device 1 includes a substantially square, flat frame 2 which has an open center portion 3 provided therein. Usually one section of the frame, indicated by the frame member 4, is wider than the remaining parts of the frame to facilitate securing indicia receiving means or similar articles thereto, as will be hereinafter described. The frame 2 may be made from any suitable

material and usually it is constructed from an attractive, serviceable wood, such as maple or walnut. The opposed portion of the frame 2, with relation to the frame member 4, is indicated by the frame member 5. Normally the frame would be positioned in a vertical plane with the frame members 4 and 5 extending vertically. It is preferred that grooves 6 and 7 be formed in the opposed face surfaces of the frame members 4 and 5, respectively, to aid in positioning the indicator means in the control device 1.

As an important feature of the invention, a plurality of carrier bars 8 are positioned in the frame center 3 in vertically spaced, parallel relation. These carrier bars 8 preferably are made from metal, such as aluminum, by an extrusion process and are of substantially "I"-shape in section so that each of the carrier bars 8 has a top flange 9 extending from both upper edges thereof and has a bottom, or base flange 10 protruding from the lower edge of each carrier bar. Usually these top and base flanges 9 and 10 are slightly curved and extend inwardly of the carrier bar towards each other, as indicated in Fig. 4 of the drawings. The carrier bars 8 are engaged with the frame 2 by having the end portions of each carrier bar snugly received in the grooves 6 and 7. Suitable spacer plates 11, usually made from metal, are secured to the frame 2 intermediate each pair of the adjacent carrier bars to aid in retaining the carrier bars in desired spaced relation and in engagement with the frame 2. Any suitable means, such as escutcheon pins 12, are used for securing the plates 11 in position.

As shown in Fig. 4, the top and bottom flanges 9 and 10 of the carrier bars 8 overhang the associated side portions of the carrier bars so that suitable indicia bearing slips or boards 13 can be engaged with such flanges on opposite sides or faces of each of the carrier bars 8 when desired, as indicated in the drawings. The slips 13 engage any given carrier bar and will usually have the same data appearing thereon with such data being the same in a direction extending from the frame member 4 towards the frame member 5, for a purpose to be described hereinafter. These slips 13 may be of any suitable construction and have any desired data thereon. The slips may be pressed into engagement with the overhanging top and base flanges or else be slid telescopically into engagement therewith before the carrier bars are secured in place in the frame 2, as desired.

Yet a further feature of the invention resides in an indicator or marker 14 one of which is in slidable engagement with one of the top or base flanges 9 or 10, respectively, of each of the carrier bars. Usually a pair of indicators 14 engage with each of the carrier bars with one indicator being positioned on the top flange and one on the base flange thereof, as shown in the drawings. Usually the indicators are of a one piece, molded construction and are made from a conventional plastic material by an injection molding operation. The indicators 14 are of substantially U-shape in section with each indicator having a pair of opposed, parallel arms 15 and 16 provided thereon. Each of these arms 15 and 16 is pointed, as indicated at 17 at the extremity thereof and extends towards the opposite flange of the carrier bar positioning same, so that the points 17 of the arms 15 and 16 are in all instances clearly associated with the indicator slips 13 carried by any given carrier bar. It should be noted that the arms 15 and 16 thus make the

slips 13 readable from either side of any carrier bar. By spacing the bars as shown, the indicators 14 can be manually moved from either side of the control or register device of the invention and the indicators 14 will be readable from any desired direction and will provide the same reading on the slips 13 regardless of which side of the device 1 a person is viewing same from. Fig. 4 shows that the indicators 14 on the inner surfaces of the arms 15 and 16 thereof, are provided with recessed portions terminating in shoulders 18 which facilitate securing a positive engagement between the indicators and the flanges of the carrier bars positioning same. All of the indicators 14 have inherent resiliency and this facilitates snapping the indicators onto or off of the flanges positioning same after the device of the invention has been completely assembled.

The data being recorded or registered by the device of the invention also is partially indicated by the use of plates 19 that are suitably secured in spaced parallel relation to the frame member 4 adjacent the upper and lower margins of the carrier bars 8 by suitable means, such as escutcheon pins 20. These plates 19 normally are provided with a pair of opposed overhanging flanges 21 so that the plates 19 can readily receive data bearing means such as cards or slips 22 in sliding engagement therewith.

In the example of the invention shown in Figs. 1 through 4, this register device is particularly adapted for use in large offices wherein a number of salesmen are employed and are in and out of the office at various times during a day. The salesmen can move the indicator devices 14 along the carrier bars provided to show when they will be in the office, or when they will return to the office or the fact that they are out of the office and will not return, all as is shown on the data bearing slips 13 carried by the carrier bars. "NR" is used on the data slips to indicate when the salesman is out and will not return that day. Two salesmen's activities are recorded on one carrier bar 8 inasmuch as there is a plate 19 provided adjacent each margin of such carrier bar. The salesmen's names, such as Smith and Jones, would appear on the data bearing card 22 provided in his indicator plate 19 and the salesman would indicate his actions by the particular indicator 14 associated with or level with his name card 22. Of course, the indicators 14 are of such size that the pointed ends 17 thereof can readily be slid by each other when two indicators are positioned by any one carrier bar on the opposed flanges thereof.

Fig. 5 of the invention shows a modified type of a device 31 of the invention wherein this special device 31 is generally similar to the device 1 and it positions a data receiving plate 32 adjacent or aligned horizontally with each of a number of carrier bars 33 positioned in the device. One indicator 34 may be slidably engaged with the upper flange of each of the carrier bars 33 whereas a pair of indicators may be associated with the lower flange of each carrier bar. A data bearing slip 35 is shown engaged with each of the carrier bars 33. Thus by using similar data bearing slips as in the device shown in Figs. 1 through 4, a salesman now can indicate, whether or not he is in, and how long and when he expects to be in the office by the time indicated between the two spaced indicators received on one flange of the carrier bar 33.

The indicia slips or indicia appearing on any given carrier bar normally would be exactly the

same on opposite surfaces on any given carrier bar, with the exception that the data would read in a direction of from right to left, for example, on one face of the device and would read from left to right on the opposite face. However, the indicia slips on different carrier bars can be different when desired. In some instances it also may be desirable to have indicia receiving means such as the carriers or slides 19 positioned on the frame member 5 as well as on the frame member 6.

The resiliency of the slides or markers 14 is thought to be facilitated by the provision of a narrow, shallow recess 50 which is provided in the base portion of the marker 14 intermediate the arms 15 and 16 provided thereon. This base portion of the marker on the inner surface thereof is contoured to mate closely with or be complementary to the outer surface of the flanges provided on the carrier bars 8. Such recess 50 is thought to help provide the desired resiliency in the base portions of the markers to permit them to be snapped onto or off of the carrier flanges provided therefor.

In the embodiment of the invention illustrated in Fig. 5, it may be particularly desirable to use different colored markers on the top flange than on the bottom flange of the carrier bar 35. Thus the marker on the top part of the carrier bar may be used to indicate whether the salesman is in or out of the office, whereas the pair of markers on the lower carrier flange may be used to indicate the time that the salesman is going to be in the office on any given day. Of course, different colored markers could be used on the other embodiment of the invention in any manner that is desired.

It will be appreciated that the indicator and recording device of the invention can be used in any desired manner for recording or controlling any desired type of data. The device will provide a convenient visual guide and control of inventories, or can be used as a sales control, a service control, a production control, a recording control, a dispatching control, et cetera. It may be desired to make up a control from multiple control units of the invention and these could be individually produced or else could be produced in a unitary type of a frame. It also may even be desirable in some instances to provide a center frame member in a frame, such as the frame 2 illustrated herein, for carrying the indicia means such as the plates 19 and slips 22. Such center frame member would extend parallel to the frame members 5 and 6 intermediate same so that the data recorded in the device of the invention could have two controls or indicators provided for the data indicated or recorded on the auxiliary center frame strip provided. Thus, for example, the operations to be performed could be indicated on one carrier bar whereas the timing for such operation could be indicated on a second carrier bar aligned with the carrier bar indicating the operations to be performed. In some instances, it may be desirable to provide slight notches in the edge portions of the flanges on the carrier bars so that the indicator means can be accurately or positively located with relation to the carrier bars and hence with relation to any data bearing slips carried thereby. Of course, it also is possible to mark the desired data integrally onto a carrier bar, such as by stenciling it thereon, or by molding it in or printing it directly on the carrier bar. The carrier

bar may, of course, be made from plastic material as well as any other suitable material.

From the foregoing, it will be realized that a sturdy, compact, control and register device has been provided by the invention. This device has an indicator member which is readily and easily movable from both exposed sides of an open center portion of the device and which visually records and indicates data that is readily readable from both sides of the control device of the invention. The indicator means used are conveniently engaged with and disengaged from the device as desired and the device is adapted for a long, useful service life without any alteration or maintenance thereof whereby it is submitted that the objects of the invention have been realized.

While several complete embodiments of the invention have been disclosed herein, it will be appreciated that modification of these particular embodiments of the invention may be resorted to without departing from the scope of the invention as defined by the appended claims.

Having thus described my invention, what I claim is:

1. An indicator device comprising a frame having an open center portion, said frame having opposed grooves formed in a pair of opposed sides of the open center portion thereof, a plurality of carrier bars the ends of which are received in said grooves to position such bars in said frames, said carrier bars having side portions, spacer means for accurately locating said carrier bars, said carrier bars being roughly of I-shape in section and having inwardly curved base and top flanges, indicia means associated with both of the side portions of said carrier bars, indicia receiving means on said frame at the ends of said carrier bars, and indicators slidably engaged with the said top flanges of said carrier bars and extending downwardly over both sides thereof, said indicators being roughly of inverted U-shape in section and having shoulders on the opposed inner surfaces thereof for engaging the top flanges of said carrier bars, said indicators being resilient and adapted to be sprung into and out of engagement with said carrier bar flanges, other indicators being engaged with said bottom flanges of said carrier bars to extend upwardly therefrom into association with both sides of said carrier bars.

2. An indicator device comprising a frame having an open center portion, said frame having opposed grooves formed in a pair of opposed sides defining the center portion thereof, a plurality of carrier bars the ends of which are received in said grooves and thereby positioned in said frames, spacer means in said grooves for accurately locating said carrier bars, said carrier bars being roughly of I-shape in section and having inwardly curved base and top flange portions, indicia means on the sides of said carrier bars, indicia receiving means on said frame adjacent the end of each of said carrier bars, and resilient molded indicators slidably engaged only with the top flanges of said carrier bars and extending downwardly over both sides thereof, said indicators being roughly of inverted U-shape in section, other indicators being engaged only with said base flanges to extend upwardly therefrom into association with both sides of said carrier bars, the indicators being resilient to be sprung into and out of engagement with the top and base flanges, the indicators on the top and base flanges of any one said carrier bar extending to-

wards each other and being movable past each other.

3. In a control device, a frame, a plurality of carrier bars of substantially I-shape in section secured in spaced parallel relation to said frame, said carrier bars having edge flanges thereon, and a substantially U-shaped plastic indicator slidably and removably engaging one of said edge flanges only of a said carrier bar, said indicator having spaced opposed parallel arms terminating in inwardly extending flanges engaging said carrier bar's edge flange, said indicator having a base engaging an outer surface of said edge flange, said indicator having a recess extending longitudinally thereof in the inner surface of its base to aid in making the said indicator resilient to be snapped into and from engagement with said edge flange. 15
